UNITED STATES PATENT OFFICE.

EMIL LÖVINSOHN, OF CHARLOTTENBURG, GERMANY.

MANUFACTURE OF POWER-PRESS PATTERN-SHEETS.

1,125,572.

Specification of Letters Patent. Patented Jan. 19, 1915.

Application filed October 21, 1908. Serial No. 458,900.

To all whom it may concern:

Be it known that I, EMIL LÖVINSOHN, a subject of the King of Prussia, German Emperor, residing at 5 Hardenbergstrasse, Charlottenburg, Kingdom of Prussia, German Empire, have invented certain new and useful Improvements in the Manufacture of Power-Press Pattern-Sheets, of which the following is hereby declared to be a full, 10 clear, and exact description.

The invention is illustrated in the accompanying drawing, in which the single figure represents a transfer sheet on which the pattern is printed, as hereinafter explained.

Heretofore, pattern sheets printed in appropriate design have been employed for transfer of the design on to the work-sample or piece in cloth, leather or other material selected for embroidery. At times, the 15 outline design was impressed upon the pattern sheet by admixing the selected color base in dry state with melted wax serving as a carrier to effect the imprint; or else the struck sheet with its ordinary ink imprint yet moist was sprinkled over with rosin to 20 coat the fresh impression. In either instance the impression taken was capable of melting for simultaneous transfer of the color design from the pattern sheet, once a 25 hot smoothing iron was run across the back of the sheet laid face down upon the work piece. But neither plan lent itself to the striking off of numerous replica, as in customary use of the ordinary printing or lithograph 30 press equipped—among other details—with the special stereotype block bearing thereon the selected design. Nor is common printer's ink a suitable medium proper to impress a pattern sheet, especially meant 35 for the manifold transfer of the design.

My invention is based upon the discovery that certain of the anilin dye stuffs, derived from coal tar, not only melt at the usual temperature of a smoothing iron, *e. g.*, 200° 40 C., but even heighten in color under high heat and lend themselves beside to compatible blending with a non-siccative binder, the two together being taken up by the inking roll of the press in course of revolution and 45 spread as a consistent film over the raised pattern of the stereotype block preparatory to striking off the sheet. The resultant sheet *a*, bearing the design in pattern *b*, once it dries can be applied in reverse to 50 numerous work samples, and the pattern be thus repeatedly transferred by simple use of

a hot smoothing iron or roll run over the back of the flat sheet. The characteristic quality of the selected dye stuff which allows it to blend with the compatible binder 60 free from risk of decomposition and to readily melt partially or fractionally in unison at the prescribed heat, permits the pattern sheets to be run off in multiple from the familiar printing press in readiness for immediate use alone, without further preparation. 65

In usual practice, the special anilin dye stuffs such as Victoria green, Victoria blue, rhodamine or cerosin, meet the requirements 70 and having been found fit may be selected indifferently, although other anilin dyes, possessing like characteristics, may be chosen instead, if desired. Dyes of somber hue which heighten in color at the heat of the 75 smoothing-iron better express the details of the design and are preferred, accordingly.

The chosen dye stuff is admixed with some suitable binder, in moist state like printer's ink or varnish compound, nearly dry, either 80 of which will blend with the dye stuff to form a moist compound capable of easy distribution by the inking-roll of the multiple or lithographic press. Mineral oil rendered viscid by addition of some resinous material, 85 will suffice as a varnish-like binder or carrier, in which ordinary rosin, copal or the like, may serve for the resinous ingredient, although other resinous substances compatible with the selected anilin dye and melting 90 with it under heat of the smoothing iron, may be chosen instead. Aside from cheap and easy cold production in multiple at ordinary temperature in the printing press, the pattern sheets thus struck off lend themselves alone to repeated transfer onto successive work-samples at the higher heat of a 95 smoothing-iron.

The novel features of this invention consist in that the pattern is printed cold on 100 to the transfer paper and that the pigment used is not all transferred to the fabric at the first impression but the same transfer can be used to give as many as eight impressions, the last of the impressions being 105 almost as powerful as the first by virtue of the fact that the pigment used deepens by the application of heat. Another feature is that the designs executed by the present process can be printed off on a rotary or 110 similar machine at the rate of 30,000 per hour, a rate absolutely unapproachable in

any of the known processes as experiments have proved.

Having thus described my invention what I claim as new and desire to secure by Letters Patent, is:—

1. A transfer sheet bearing its chosen design medium in cold, moist imprints derived from a select anilin dye constituting the medium or agent specially fit for repeated fractional softening or melting under a hot smoothing iron.
- 10 2. The method of making a transfer pattern sheet, which consists in admixing a fit

anilin dye melting or softening fractionally at the heat of a smoothing iron together with a compatible carrier rendered viscid to properly spread under an inking roll and with such mixture imprinting the selected design cold and moist upon a pattern blank, substantially as described.

In testimony whereof I affix my signature in presence of two witnesses.

EMIL LÖVINSOHN.
